H. RUFF.

PLATE MOVING MECHANISM FOR PRESSES, PUNCHES, SHEARS, AND THE LIKE.

APPLICATION FILED JULY 12, 1918. RENEWED MAY 21, 1921.

1,384,093.

Patented July 12, 1921.

UNITED STATES PATENT OFFICE.

HERBERT RUFF, OF PHILADELPHIA, PENNSYLVANIA, ASSIGNEE OF ONE-HALF TO
LEON G. BUCKWALTER, OF MERCHANTVILLE, NEW JERSEY.

PLATE-MOVING MECHANISM FOR PRESSES, PUNCHES, SHEARS, AND THE LIKE.

1,384,098.

Specification of Letters Patent. Patented July 12, 1921.

Application filed July 12, 1918, Serial No. 244,660. Renewed May 21, 1921. Serial No. 471,523.

To all whom it may concern:

Be it known that I, HERBERT RUFF, a citizen of the United States, residing in the city and county of Philadelphia, State of Pennsylvania, have invented a new and useful Plate-Moving Mechanism for Presses, Punches, Shears, and the like, of which the following is a specification.

In the handling of plates of sheet metal, such as are commonly used in shipbuilding, boiler plants and the like, in respect to the large power punches, shears or presses employed, it is well known to those skilled in the art that these plates are frequently extensive in area and are heavy and unwieldy to manipulate with respect to the press, punch, shear or the like, frequently requiring the assistance of several laborers in addition to the operative of the punch or press, in order to properly position them with respect to the punch, shear or other implement.

It has heretofore been the practice to manipulate or joggle these plates and position them with respect to the punching, pressing or shearing implement either through the aid of several laborers or by a type of machine, which takes up considerable space, is somewhat cumbersome and whose first cost is greatly in excess of my present invention which is designed to obviate the foregoing disadvantages and consists in its broad aspects of a power-driven, self-contained and readily portable plate moving mechanism for moving plates in any desired direction in a horizontal plane with respect to power or hydraulic presses, punches, shears or the like.

In carrying out my invention, I employ a suitable portable framework on which is supported an electric or other motor connected by suitable gearing to a plate actuating wheel, which is located below and normally out of contact with the plate, said wheel having its periphery roughened or serrated and being adapted at the will of the operator to be intermittently or continuously rotated and capable of being simultaneously raised into contact with the under surface of the plate so as to propel or actuate the latter horizontally in the desired direction, suitable means being provided for lowering and changing the vertical line of rotation of said actuating wheel, so that the

plate can be actuated in any desired lateral direction, forward, back or sidewise, or diagonally according to requirements.

To the above ends, my invention consists of the novel construction of a hardened, peripherally notched or serrated wheel revolving intermittently or continuously about a horizontal axis, power being taken from a small electric or other motor equipped with suitable speed reducing mechanism in conjunction with manually operated means under the control of the operator for raising and lowering and changing the line of rotation of said wheel with respect to the plate, according to requirements.

The electric motor can be operated continuously or intermittently as desired, according to requirements, by means of a push button, switch or the like of any conventional type which can be conveniently located with respect to the hand of the operator, so that a single operator can efficiently manipulate the punching and plate moving mechanism with one handle or hand.

It further consists of the novel construction of vertical shaft carrying the plate actuating wheel, a gear keyed to the lower portion of said shaft and a manually operated segment in mesh with said gear for changing the position of said vertical shaft and wheel.

It further consists of the novel combination of the plate actuating wheel, a vertical shaft therefor, a laterally movable handle and means carried by said handle for elevating or lowering said shaft and wheel during the rotation of the latter.

For the purpose of illustrating my invention, I have shown in the accompanying drawing one form thereof which is at present preferred by me, since the same will be found in practice to give satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a side elevation of a plate moving mechanism for moving plates in a horizontal plane, embodying my invention.

Fig. 2 represents, on an enlarged scale, a

side elevation of a portion of Fig. 1, certain of the parts therein being shown in section.

Fig. 3 represents a perspective view of a portion of the plate moving mechanism in detached position.

Similar numerals of reference indicate corresponding parts in the figures.

Referring to the drawings,

10 1 designates my novel construction of plate moving mechanism for power punches, presses, shears and the like, the same comprising a suitable portable supporting frame 2, consisting of a base portion 3 and
15 an upright rear portion 4, which has a laterally, forwardly extending bed 5, on which is supported a small electric or other motor 6, which may be of any conventional type and adapted to be continuously or intermittently rotated, as will be evident to those
20 skilled in the art.

7 designates the motor shaft, which carries the outer and inner spur gears 8 and 9, which are in mesh with the spur gears 10 and 11 respectively, which are mounted on the shaft 12, which rotates in the bearings 13 on preferably the top of the motor 6, said gear 9 being loose on the shaft 7 and traveling at a much lower speed than said shaft.

30 It will be noticed that the gears 8 and 11 are of relatively small diameter as compared with the intermeshing gears 9 and 10, for the purpose of reducing the speed of rotation of the bevel gear 9 and the bevel gear 14 there-
35 on to the desired extent, said gears 9 and 14 being connected by the sleeve 7* loosely mounted on shaft 7.

15 designates a double bevel gear whose lower gear teeth 16 are in mesh with the bevel gear 14 and whose upper teeth 17 are in mesh with the bevel gear 18, which is secured to or integral with the hardened, peripherally notched or serrated plate actuating or joggling wheel 19, whose outer periphery appears as best seen in Figs. 2 and 3, being roughened, serrated or notched, said wheel 19 and gear 18 being freely revoluble upon the horizontal shaft or stud 21, which projects laterally from the top of the vertical shaft 22, which has its lower portion 23 of reduced diameter, and is rotatably mounted in the vertical bearing 24, the shoulder 25 serving as a stop to arrest or limit the downward movement of the parts 22, 23 and particularly to determine the normal position of the wheel 20. The double bevel gear 15 composed of the gears 16 and 17 revolves loosely on its shaft or bearing 22.

26 designates a pinion which is fast to the shaft 23 and which is engaged by the curved rack or segment 27 mounted on the arm 28 which is fulcrumed at the point 29 and terminates in the handle 30.

31 designates a manually operated lever normally retained in the position seen in

Fig. 2, by the spring 32, said lever being pivoted at 33 to the link 34, whose lower end 35 is attached to a toggle or cam member 36, fulcrumed at 37 and having its upper end in contact with the under side of the bottom 70 flange or terminal 38 of the shaft 23.

39 designates a plate to be punched, sheared or otherwise treated and 40 designates a punch or press of any conventional type. It will be understood that only a slight upward movement of the shaft 22 and its adjuncts is required to bring the plate joggling wheel 19 into contact with the bottom of the plate 39, and that the gears 14 and 16 are so constructed in practice that they will be in mesh at all times. 75 80

I have shown in the present instance a simple form of cam or eccentric 36 employed as a raising and lowering device for the shafts 22 and 23 and their adjuncts, said cam being fulcrumed at the point 37 in the ears 41 which may be cast or secured to the ledge 42 but it will be evident that any other equivalent device as a suitable toggle mechanism may be employed if desired. 90

The operation is as follows:—

The parts normally appear as seen in Fig. 2, the plate actuating wheel 19 being slightly below and out of contact with the under surface of the plate 39 which it may be desired to shift horizontally. The wheel 19 may be revolved continuously or intermittently at the will of the operator by causing the continuous or intermittent rotation of the motor shaft 7 by any suitable form of push button, switch or the like, 43, the construction and operation of which, I have deemed it unnecessary to describe in detail.

It will be apparent that so long as the wheel 19 is below and out of contact with the under surface of the plate 39, as seen in Fig. 2, no movement of the latter can occur. When, however, it is desired to actuate the plate 39, the operator causes the wheel 19 to rotate by closing the circuit of the motor 6 and upon gripping the handle 30 and pressing on the lever 31, so that the parts assume the position seen at the left of Fig. 1, it will be apparent that the toggle, cam or its equivalent, 36, will assume the position seen in Fig. 1, whereupon the vertical shaft composed of the parts 22 and 23, the gear 26, the horizontal shaft 21 and the wheel 19, will be elevated, until the latter is in contact with the under surface of the plate 39 and the latter will then be actuated or propelled in a forward, rearward, sidewise or diagonal direction to the desired extent at the will of the operator, it being understood that gears 17 and 18 are so constructed that their teeth will always be in mesh when the wheel 19 is in its raised position, as seen in Fig. 1, or in depressed position, as seen in Fig. 2.

The spur pinion 26 being fast to the upright shaft 23 and the horizontal shaft or 130

stud 21 carrying the wheel 19 being secured to the shaft 22, as will be understood from Fig. 2, it will be apparent that when the handle 30 of the arm 28 of the segment 27 is moved laterally or horizontally about its fulcrum point 29, axial rotation to the desired extent will be imparted to the pinion 26 and shafts 22 and 23 and their adjuncts, so that the said hardened notched or serrated wheel 19 will be rotated about a vertical axis consequently permitting it to assume any desired position at the will of the operator. For example, when the notched wheel 19 is laterally rotated 180 degrees from the position seen in the top of its periphery then travels in a direction opposite to that of its original position and hence a reversal of the line of travel of the plate 39 is accomplished by merely turning the long handle 30 through a relatively small arc. When the vertical shaft composed of the members 22 and 23 is depressed by releasing the hand grip or lever 31 and cam or toggle 36 or its equivalent, the parts will assume the normal position seen in Fig. 2 again, whereupon the notched wheel 19 is disengaged from the bottom surface of the plate 39 and the latter remains at rest.

It is obvious that the motor can be operated continuously or at intervals as desired, by placing a push button, switch or the like 43 on the hand lever 30, and, if desired, the entire device and particularly the gearing may be contained within a light sheet metal casing.

If desired, further control can be effected by placing a push button switch on the handle 30 to control the electric solenoid of the customary construction which operates the engaging clutch of the punch if power driven or the controlling valve in the case of a hydraulic punch, whereby with this latter arrangement one operator can completely manipulate the punching and moving of the plate by one hand and where an electric current is not available, a small pneumatic engine as the motor of a pneumatic drill or the like can be substituted for an electric motor, as will be apparent to those skilled in the art.

I have deemed it unnecessary to describe in detail these various embodiments of the use of my invention as their general construction and mode of application will be apparent to those skilled in the art.

It will be seen from the foregoing that my present invention is light and portable and can be readily moved from one machine to the other according to whichever character of machine may be temporarily in use, as a punch, press or shear, and if desired the rear upright as 4 can be bolted or clamped to the front of the punch, press or shear which may be in use.

65 In practice, I may make the bed or base

2 and the upright portion or bracket 4 of a single casting and bolt the vertical bearing 24 and the bed 5 which supports the motor 6 to said upright bracket as seen in Fig. 1 or I may make all the parts 4 and 70 24 in a single casting as seen in Fig. 3.

In Fig. 2, I have shown one convenient form of mounting the push button, switch or its equivalent 43 upon the handle 30, said push button being electrically connected to the motor by a two wire flexible cable 44 suitably fastened in place by small insulating clips as 45, so arranged as to permit the free lateral movement of the handle 30 about the fulcrum point 29. 46 designates 80 a standard lamp socket or other plug or any suitable electric current tapping device, which is secured to the double wire flexible cable 47 which is connected at its other end as 48 to the power terminals of the motor, 85 said cable serving to conduct power to the motor 6 and being preferably made so as to be adapted to the conventional wiring of the building or shop where the device is installed. I have omitted the push-button, wiring and their adjuncts from Fig. 1 for the sake of clearness of illustration but it will be apparent from Fig. 2 that the motor can run intermittently or continuously at the will of the operator and its operation 95 can be controlled by the same hand which positions the plate actuating wheel 19. I am the first in the art to employ a device of this character and my claims thereto are to be interpreted in accordance with the 100 scope accorded to inventions of this character.

It will now be apparent that I have devised a novel and useful construction of a plate moving mechanism for presses, 105 punches and shears which embodies the features of advantage enumerated as desirable in the statement of the invention and the above description, and while I have, in the present instance, shown and described a 110 preferred embodiment thereof which will be found in practice to give satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:—

1. In a device of the character stated, the combination of a peripherally notched or serrated plate actuating wheel located normally below and out of contact with the plate to be moved, means for rotating said 125 wheel and pivotally mounted manually operated means for elevating said wheel into contact with the under surface of the plate to be moved.

2. In a device of the character stated, the 130

combination of a hardened, peripheral, notched or serrated wheel located normally below and out of contact with the plate to be moved, means for rotating said wheel, 5 means for elevating said wheel into contact with the under surface of the plate to be moved, and means for varying the plane of rotation of said wheel.

3. The combination of a suitable frame-
10 work, a vertical shaft rotatably mounted therein, a stud projecting laterally from said shaft, a notched or serrated wheel carried by said stud and having gear teeth thereon, a gear loosely mounted on said vertical shaft, and means for rotating said gear.

4. The combination of a suitable frame-
work, a vertical shaft rotatably mounted therein, a stud projecting laterally from 20 said shaft, a notched or serrated wheel carried by said stud and having gear teeth thereon, a gear loosely mounted on said vertical shaft, and means for rotating said gear.

25. 5. The combination of a portable supporting frame, a vertical shaft therein, a stud projecting laterally from said shaft, a notched or serrated wheel carried by said stud and having a bevel gear thereon, a gear 30 loosely mounted on said vertical shaft and in mesh with said bevel gear, means for rotating said gear, and means for raising and lowering said shaft and wheel into and out of contact with the plate to be moved.

35. 6. The combination of a portable supporting frame, a vertical shaft therein, a stud projecting laterally from said shaft, a notched or serrated plate actuating wheel carried by said stud and having a bevel 40 gear thereon, a gear loosely mounted on said vertical shaft, means for rotating said gear, means for axially rotating said vertical shaft and means for raising and lowering said vertical shaft and plate actuating wheel.

45. 7. In a device of the character stated, a portable frame comprising a lower base portion, an upright portion and a bed laterally extending therefrom, a motor mounted on said bed, a vertical shaft having its 50 bearing in said frame, a shoulder on said shaft to limit its downward movement, a double bevel gear loosely mounted on said vertical shaft, a motor shaft, a bevel gear on said motor shaft and in mesh with the lower portion of said double bevel gear, a shaft 55 projecting laterally from the top of said vertical shaft, a plate actuating wheel loosely mounted on said lateral shaft, and a bevel gear on the side of said wheel and in mesh with the upper portion of said double bevel gear, in combination with means for raising and lowering said vertical shaft and its adjuncts, and means for axially rotating said vertical shaft and wheel.

60. 8. In a device of the character stated, a portable frame comprising a lower base portion, an upright portion and a bed laterally extending therefrom, a motor mount- 65

ed on said bed, a vertical shaft having its bearing in said frame, a shoulder on said shaft to limit its downward movement, a double bevel gear loosely mounted on said vertical shaft, a motor shaft, a bevel gear 70 on said motor shaft and in mesh with the lower portion of said double bevel gear, a shaft projecting laterally from the top of said vertical shaft, a plate actuating wheel loosely mounted on said lateral shaft, and a bevel gear 75 on the side of said wheel and in mesh with the upper portion of said double bevel gear, in combination with means for raising and lowering said vertical shaft and wheel.

80. 9. In a device of the character stated, a portable frame comprising a lower base portion, an upright portion and a bed laterally extending therefrom, a motor mounted on said bed, a vertical shaft having its bearing in said frame, a shoulder on said shaft to limit its downward movement, a double bevel gear loosely mounted on said vertical shaft, a motor shaft, a bevel gear 85 on said motor shaft and in mesh with the lower portion of said double bevel gear, a shaft projecting laterally from the top of said vertical shaft, a plate actuating wheel loosely mounted on said lateral shaft, and a bevel gear 90 on the side of said wheel and in mesh with the upper portion of said double bevel gear, in combination with means for raising and lowering said vertical shaft and wheel.

95. 10. In a device of the character stated, a portable frame comprising a lower base portion, an upright portion and a bed laterally extending therefrom, a motor mounted on said bed, a vertical shaft having its bearing in said frame, a shoulder on said shaft to limit its downward movement, a double bevel gear loosely mounted on said vertical shaft, a motor shaft, a bevel gear on said motor shaft and in mesh with the lower portion of said double bevel gear, a shaft 100 projecting laterally from the top of said vertical shaft, a plate actuating wheel loosely mounted on said lateral shaft, and a bevel gear on the side of said wheel and in mesh with the upper portion of said double bevel gear, in combination with means for raising and lowering said vertical shaft and its adjuncts, and means for axially rotating said vertical shaft and wheel.

105. 11. In a device of the character stated, a portable frame comprising a lower base portion, an upright portion and a bed laterally extending therefrom, a motor mounted on said bed, a vertical shaft having its bearing in said frame, a shoulder on said shaft to limit its downward movement, a double bevel gear loosely mounted on said vertical shaft, a motor shaft, a bevel gear on said motor shaft, and in mesh with the lower portion of said double bevel gear, a shaft 110

120

125

130

- projecting laterally from the top of said vertical shaft, a plate actuating wheel loosely mounted on said lateral shaft, and a bevel gear on the side of said wheel and 5 in mesh with the upper portion of said double bevel gear, in combination with a pinion fast to the lower end of said vertical shaft, a segment fulcrumed to said motor supporting bed and in mesh with said pinion, and means for laterally moving said segment.
12. In a device of the character stated, a portable frame comprising a lower base portion, an upright portion, and a bed laterally 15 extending therefrom, a motor mounted on said bed, a vertical shaft having its bearing in said frame, a shoulder on said shaft to limit its downward movement, a double bevel gear loosely mounted on said vertical shaft, a motor shaft, a bevel gear on said motor shaft and in mesh with the lower portion of said double bevel gear, a shaft projecting laterally from the top of said vertical shaft, a plate actuating wheel loosely 20 mounted on said lateral shaft, and a bevel gear on the side of said wheel and in mesh with the upper portion of said double bevel gear, in combination with a pinion fast to the lower end of said vertical shaft, a segment in mesh with said pinion, a handle attached to said segment, cam mechanism for the lower end of said shaft, and means carried by said handle for actuating said cam mechanism to raise or lower said vertical 25 shaft and wheel.
13. In a device of the character stated, means for actuating a plate, manually controlled devices provided with a handle for positioning said means, a handle for said devices and an electric control for said means carried on said handle.
14. In a device of the character stated, rotary means for actuating a plate by contact with the bottom thereof, electrically con- 30 trolled devices for operating said rotary means, and devices for changing the plane of rotation of said rotary means.
15. In a device for joggling heavy metal plates, a rotary plate joggling wheel having a serrated periphery, electrically controlled devices for rotating said wheel, and manually operated devices for raising and lowering said wheel.
16. In a device for joggling heavy metal plates, a rotary plate joggling wheel, electrically controlled devices for rotating said wheel, manually operated devices for raising and lowering said wheel, and manually operated devices for changing the plane of rotation of said wheel.
17. In a device of the character stated, a serrated wheel located below and normally out of contact with the plate to be joggled, means for rotating said wheel, means for changing the plane of rotation of said wheel, 65 a handle on said latter means, a cam located below said wheel, and devices pivotally mounted on said handle and connected with said cam for actuating the latter.
18. The combination of a revoluble plate 70 joggling wheel, means for rotating said wheel, manually operated means for raising and lowering said plate joggling wheel, and manually operated means for changing the plane of rotation of said plate joggling 75 wheel.
19. The combination of a plate joggling wheel, means for rotating it, a manually operated lever, means actuated by said lever for changing the plane of rotation of said 80 wheel, and manually operated means carried by said lever for raising and lowering said wheel.

HERBERT RUFF.
